United States Patent Office.

JOHN REISER, OF TRENTON, NEW JERSEY.

Letters Patent No. 91,163, dated June 8, 1869.

IMPROVED DOOR-PULLEY.

The Schedule referred to in these Letters Patent and making part of the same.

To all whom it may concern:

Be it known that I, JOHN REISER, of Trenton, in the county of Mercer, and State of New Jersey, have invented a new and useful Improvement in Door-Pulleys; and I do hereby declare that the following is a full and exact description of the same, reference being had to the accompanying drawings, and to the letters of reference marked thereon, in which—

Figure 1 represents a door secured by my device.

Figure 2 represents an upper section of the weight.

Figure 3 shows a perspective view of my improvement.

This invention consists in attaching, to the sliding weight on the inner side of a door or casing, a thumb or set-screw, which operates on a slide-bar, and permanently secures the weight at any point on the bar, so that, when the door is closed, it cannot be opened without loosening the set-screw, thus graduating the distance, and preventing the door from being opened wider than desired; and the door is secured by a chain or cord, one end of which is attached to the door or casing, and the other to the weight, obviating the necessity of a bolt on the inner side of the door.

To enable others to make use of my invention, I will proceed to describe the same.

Similar letters of reference denote like parts in the drawings.

A is a sliding weight, placed on the inner side of the door, or on the casing. When placed in the latter position, I use three pulleys instead of one, two of which are on the casing, and one upon the door.

B is a thumb or set-screw, attached to weight A and operating against slide-bar C.

d d are caps at the upper, and near the lower ends of weight A, used for covering the cavities by which the weight is loaded or made lighter.

This thumb or set-screw, placed on the weight, and pressing against the slide-bar, will effectually prevent the working of the weight, and constitutes a permanent fastening when the door is closed, and more secure than any lock or bolt, as it cannot be picked from the outside. It can be placed on any part of the door or casing, and, when the set-screw is turned against the slide-bar, on any point of the bar, the door cannot be opened wider, unless the cord or chain is broken.

I am aware that Peter Joseph Tillmann, of Trenton, New Jersey, obtained a patent, dated April 6, 1869, for the combination of the weight, slide-bar, swivel-pulley, and cord. These I do not claim; but

What I do claim, and desire to secure by Letters Patent, is—

The thumb or set-screw B, applied to the weight A, when arranged, constructed, and combined as herein shown and represented, for the purposes set forth.

In testimony whereof, I have signed my name to this specification, in the presence of two subscribing witnesses.

JOHN REISER.
